Int. Cl. D14—01

U.S. Cl. D26—14

FIG. 1

FIG. 2

FIG. 3

Dec 219,593

PAGE 2

FIG. 4

FIG. 5

FIG. 6

FIG. 1 is a top plan view of a facsimile transmitter showing my new design;

FIG. 2 is a front elevation thereof;

FIG. 3 is a left-side elevation thereof;

FIG. 4 is a bottom plan view thereof;

FIG. 5 is a rear elevation thereof;

FIG. 6 is a right side elevation thereof; and

FIG. 7 is a front perspective view thereof.

I claim:

The ornamental design for a facsimile transmitter, substantially as shown and described.
